CLAIM

The ornamental design for an electronic view finder for a digital camera, as shown and described.

DESCRIPTION

FIG. 1 is a rear, bottom and left side perspective view of an electronic view finder for a digital camera, showing my new design;

FIG. 2 is a front, top and right side perspective view thereof;

FIG. 3 is a front, bottom and right side perspective view thereof;

FIG. 4 is a front elevational view thereof;

FIG. 5 is a rear elevational view thereof;

FIG. 6 is a top plan view thereof;

FIG. 7 is a bottom plan view thereof;

FIG. 8 is a right side elevational view thereof; the opposite side being a mirror image thereof;

FIG. 9 is a front, top and right side perspective view thereof with an eyepiece part turned 90 degrees;

FIG. 10 is a front elevational view thereof with the eyepiece part turned 90 degrees;

FIG. 11 is a rear elevational view thereof with the eyepiece part turned 90 degrees;

FIG. 12 is a top plan view thereof with the eyepiece part turned 90 degrees;

FIG. 13 is a bottom plan view thereof with the eyepiece part turned 90 degrees; and,

FIG. 14 is a right side elevational view thereof with the eyepiece part turned 90 degrees; and the opposite side being a mirror image thereof.
